(57) CLAIM

The ornamental design for a combined gift bag and transaction card, as shown and described.

DESCRIPTION

FIG. 1 is a front, perspective view of a combined gift bag and transaction card showing a first embodiment of our new design.

FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front, perspective view of a combined gift bag and transaction card showing a second embodiment of our new design.

FIG. 10 is a rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The features shown in broken lines are portions of the combined gift bag and transaction card forming no part of the claimed design. The features shown in long dash-short dash bolded broken lines indicate the bounds of the claimed design and otherwise form no part of a claimed design.

1 Claim, 12 Drawing Sheets
